UNITED STATES PATENT OFFICE.

GUSTAV SEHRT, OF ST. LOUIS, MISSOURI.

SHEET-SEVERING DEVICE.

Application filed January 29, 1923. Serial No. 615,614.

To all whom it may concern:

Be it known that I, GUSTAV SEHRT, a citizen of the United States, residing at St. Louis, Missouri, have invented a certain new and useful Improvement in Sheet-Severing Devices, of which the following is a full, clear, and exact description, such as will enable others skilled in the art to which it appertains to make and use the same.

10 This invention relates to sheet cutting machines.

In one system of bookkeeping that is now generally used by companies which have a large number of accounts on their books the 15 daily sales are entered on a sheet on which is placed the names of customers who make purchases and the amounts of the purchases, said sheet is then cut into narrow strips, each of which contains the name of a customer and the amount of his purchase, and thereafter, said strips are arranged in alphabetical order and are used in the operation of posting the daily sales in the ledgers.

The main object of my invention is to 20 provide an apparatus of simple construction, by means of which a daily sales sheet of the kind mentioned can be severed quickly and accurately into a number of narrow strips.

Another object of my invention is to 25 provide a sheet severing apparatus of the kind referred to that is equipped with a novel means for adjusting the apparatus so as to vary the width of the strips formed from the sheet.

30 Figure 1 of the drawings is a top plan view of my improved sheet severing apparatus.

Figure 2 is an end view of said apparatus, partly in section; and

35 Figure 3 is an enlarged side elevational view of a portion of the apparatus illustrating certain parts of the sheet feeding means.

Referring to the drawings, A designates a 40 horizontally-disposed table that is adapted to receive a sheet α provided with names and amounts placed opposite said names, 45 1 designates a guide or stop on said table against which one of the longitudinal edges of the sheet α is placed, B designates a cutting device formed preferably by a lever or 50 pivotally mounted member arranged at one end of the table A and provided with a blade for severing the sheet α into narrow strips, C designates feed rolls that project upwardly through openings in the table A, as 55 shown in Figure 1, and D designates spring-

pressed rolls for clamping the sheet against the rolls C, and thus causing the sheet to be fed forwardly when the rolls C are operated. The table A is provided at its discharge end with a trough E for receiving and holding the strips that are formed by severing the sheet A transversely of its length, and the cutting device B is so arranged that when it is depressed or operated 60 it will sever the end portion of the sheet α that projects forwardly beyond the end of the table, thereby causing the strip formed by the severed portion of the sheet to drop downwardly into the trough E at the end of 70 the table.

It is immaterial whether the apparatus is provided with one or more pairs of rolls for feeding the sheet α longitudinally of the 75 table into position to be engaged by the cutting device B, but I prefer to provide the apparatus with two feeding rolls C and two spring-pressed rolls D, the rolls D being rotatably mounted on a horizontally-disposed shaft 2 arranged transversely above the table 80 A and provided at its ends with angularly-disposed extensions connected to bearings 3 on the table and combined with springs 4 in such a way that the shaft 2 will be pressed downwardly, thereby causing the rolls D to 85 clamp the sheet against the feed rolls C. The feed rolls C are rigidly connected to a horizontally-disposed drive shaft 5 arranged transversely of the table A on the underside of same, and means is provided for causing 90 said shaft and the feed rolls C to turn forwardly when the cutting device B is raised or moved upwardly into the position shown in broken lines in Figure 2, at the termination of the operation of severing a strip from the sheet α . In the form of my invention herein illustrated the means that is used for this purpose consists of a vertically-reciprocating rack 6 at one side of the table that meshes with a pinion 7, a pivotally mounted 100 pawl 8 on said pinion that is adapted to cooperate with a ratchet 9 rigidly connected to one end of the feed shaft 5 that carries the feed rolls C, an angularly-disposed arm 10 that projects downwardly from the pivoted 105 end of the cutting device B, as shown in Figure 2, and a link 11 and bell crank lever 12 for transmitting movement from the arm 10 on the cutting device to the rack 6 when the cutting device B is swung upwardly. 110 As shown in Figure 2, the bell crank lever 12 is pivotally mounted on a bracket 13 on

the underside of the table A and is provided with a relatively long, horizontally-disposed arm which is joined by a slot and pin connection to the lower end of the rack 6. The 5 link 11 is joined at one end by a slot and pin connection to the short vertical arm of the bell crank lever 12, and the opposite end of said link projects outwardly through an adjustable stop 14 and is provided with a 10 head 15 that is adapted to be engaged by the arm 10 on the cutting device when said cutting device is swung upwardly.

In using the apparatus the sheet α is arranged on the table A in such a manner 15 that the top portion of said sheet which contains the first name will project forwardly beyond the end of the table and overhang the trough E, it being of course understood that it is necessary to raise the cutting device B in order to permit the sheet α to be moved forwardly beyond the end of the table. When the cutting device B is depressed the projecting end portion of the sheet will be severed into a strip which falls 20 downwardly into the trough E. Thereafter, the operator swings the cutting device B upwardly into the position shown in broken lines in Figure 2, so as to cause the angularly-disposed arm 10 on said cutting device 25 to push the link or rod 11 inwardly, thereby causing the bell crank lever 12 to move the rack 6 upwardly. As the pinion 7 that operates with said rack is provided with a pawl 8 that engages a ratchet 9 on the feed 30 roll shaft 5, the upward movement imparted to the rack 6 will cause the feed rolls C to turn forwardly, and thus feed the sheet α forwardly beyond the end of the table into such a position that when the cutting device 35 B is thereafter depressed, the projecting portion of the sheet will be severed into a strip which falls downwardly into the trough E.

If it is desired to vary the width of the 40 strips formed by transversely severing the sheet α , this can be accomplished easily by changing the position of the stop 14 against which the head 15 on the rod 11 strikes during the upward movement of the cutting device B. The stop 14 is screwed into a bearing 16 on the underside of the table, and if it is desired to increase the width of the 45 strips, said stop 14 is screwed further into the bearing 16, so as to permit of a greater movement of the link 11 before the head thereon strikes against said stop. If it is desired to reduce the width of the strips, the 50 stop 14 is screwed outwardly so as to reduce the length of the stroke of the link 11 when it is actuated by the arm 10 on the cutting device B.

A spring 17 is preferably connected to an extension 18 on the pivoted end of the cutting device B, so as to tend to balance said 55 device when it is in its raised position, but

the tension of said spring is not great enough to raise the cutting device B after said device has been depressed to sever the sheet. Any suitable means can be used for restoring the rack 6 and the parts associated with same to starting position after the arm 10 on the cutting device B moves out of engagement with the rod or link 11, such, for example, as a spring 19 on the underside of the table that exerts pressure on the long 60 arm of the bell crank lever 12 in such a direction as to move the rack 6 downwardly. 75

With an apparatus of the construction above described it is possible to quickly and accurately sever a daily sales sheet into a 80 number of narrow strips, owing to the fact that the sheet feeding means is combined with the cutting device B in such a way that the sheet will be fed forwardly a distance equal to the width of a strip each time the cutting device is swung upwardly preparatory to the operation of severing the next strip. The apparatus is of such simple construction that it can be manufactured at a 85 low cost and is not liable to get out of order when in use, and still another desirable feature of such an apparatus is that it can be adjusted easily to vary the width of the strips by simply changing the position of the stop 14. 90

Having thus described my invention, what I claim as new and desire to secure by Letters Patent is:

1. An apparatus for severing a sheet into narrow strips, comprising a table adapted 100 to have a sheet positioned thereon, a cutting device arranged beyond one end of said table for severing the sheet into narrow strips, means for receiving the severed strips and collecting and holding them in a pile, a rotatable feeding device for moving the sheet into position to be acted upon by said cutting device, an actuating mechanism for imparting a step by step movement to said feeding device, and means on 105 the cutter that is adapted to engage said actuating mechanism and impart movement to same when the cutter moves into its inoperative position.

2. An apparatus for severing a sheet into narrow strips, comprising a table adapted 110 to have a sheet positioned thereon, a plurality of feed rolls that project upwardly through openings in said table, spring-pressed rolls for pressing the sheet against 115 said feed rolls, a pivotally-mounted cutting device arranged beyond one end of the table for severing the sheet transversely of its length, means for receiving the severed portions and causing them to collect in a pile, one above the other, a pawl and ratchet mechanism arranged at one of the side edges of the table for actuating said feed rolls, and means operated by the movement 120 of said cutting device in one direction for 125

causing said pawl and ratchet mechanism to turn the feed rolls in a direction to move the sheet into position to be engaged by said cutting device.

- 5 3. An apparatus for severing a sheet into narrow strips, comprising a table adapted to have a sheet positioned thereon, a pivotally mounted cutting device arranged beyond one end of said table for severing the
10 sheet into narrow strips, means projecting beyond the end of the table for receiving and collecting the severed strips, a feed shaft arranged transversely of the table and provided with rolls for moving the sheet
15 into position to be acted upon by said cutting device, a ratchet on one end of said feed shaft, a pinion on said shaft provided with a pawl that is adapted to engage and move said ratchet, a reciprocating rack in
20 mesh with said pinion, and means arranged transversely of the table on the underside of same and adapted to be operated by the movement of said cutting device into its elevated position for reciprocating said
25 rack.
4. An apparatus for severing a sheet into narrow strips, comprising a table adapted to have a sheet positioned thereon, a pivotally mounted cutting device arranged at
30 one end of said table for severing the sheet into narrow strips, means for receiving and

collecting the severed strips, a feed shaft provided with rolls for moving the sheet into position to be acted upon by said cutting device, a ratchet on said feed shaft, 35 a pinion provided with a pawl that is adapted to engage and move said ratchet, a reciprocating rack in mesh with said pinion, an angularly-disposed arm on the pivoted end of said cutting device, and a link 40 and lever interposed between said arm and rack for actuating said rack.

5. An apparatus for severing a sheet into narrow strips, comprising a table adapted to have a sheet positioned thereon, a pivotally mounted cutting device arranged at one end of said table for severing the sheet into narrow strips, means for receiving and collecting the severed strips, a feed shaft provided with rolls for moving the sheet 45 into position to be acted upon by said cutting device, a ratchet on said feed shaft, a pinion provided with a pawl that is adapted to engage and move said ratchet, an angularly-disposed arm on the pivoted end of 50 said cutting device, a link and lever interposed between said arm and rack for actuating said rack, and an adjustable stop arranged so that it will co-operate with a head on said link to control the movement 55 imparted to said rack by the cutting device. 60
